TOY TUG BOAT

Norman L. Thompson, Erie, Pa., assignor to Louis Marx
& Co., Inc., New York, N.Y., a corporation of New York

Filed May 5, 1965, Ser. No. 85,103

Term of patent 14 years

(Cl. D34—15)

FIG. 1 is a top plan view of a tug boat embodying my new design;

FIG. 2 is a side elevational view thereof;

FIG. 3 is a bottom plan view thereof;

FIG. 4 is a front end view thereof; and

FIG. 5 is a rear end view thereof.

I claim:

The ornamental design for a toy tug boat, as shown.
